Primary Examiner — Philip S Hyder*Assistant Examiner* — Darlington Ly(74) *Attorney, Agent, or Firm* — Pearne & Gordon LLP(57) **CLAIM**

The ornamental design for a fascia for an all-terrain vehicle, as shown and described.

DESCRIPTION

FIG. 1 is a perspective view of our new invention;
 FIG. 2 is a front view thereof;
 FIG. 3 is a top view thereof;
 FIG. 4 is a right view thereof, a left view being a mirror image thereof;
 FIG. 5 is a rear view thereof; and,
 FIG. 6 is a bottom view thereof.
 The broken lines shown in the drawings illustrate portions of the fascia for an all-terrain vehicle that forms no part of claimed design.
